Primary Examiner — Deanna L Pratt(74) *Attorney, Agent, or Firm* — Cantor Colbun LLP(57) **CLAIM**

We claim, the ornamental design for a tool, as shown and described.

DESCRIPTION

FIG. 1 is a perspective view of the invention;

FIG. 2 is a top view of the design of FIG. 1;

FIG. 3 is a bottom view of the design of FIG. 1;

FIG. 4 is a first end view of the design of FIG. 1;

FIG. 5 is a second end view of the design of FIG. 1;

FIG. 6 is a first side view of the design of FIG. 1;

FIG. 7 is a second side view of the design of FIG. 1; and,

FIG. 8 is a reverse perspective view of the design of FIG. 1. The broken lines in the drawings illustrate portions of the tool that form no part of the claimed design.
